Primary Examiner — David Muller

CLAIM

The ornamental design for a medical device housing, as shown and described.

DESCRIPTION

FIG. 1 is a perspective view of a medical device housing showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is another perspective view thereof, shown in a position of use with two medical devices.

Broken lines immediately adjacent shaded areas represent bounds of the claimed design. Broken lines of the medical devices of FIG. 8 are directed to environment. All other broken lines are directed to environment or unclaimed features. The broken lines form no part of the claimed design.

The medical device housing may encompass a wall transformer for providing power to medical devices.
